UNITED STATES PATENT OFFICE.

DANIEL W. HOGE, OF CHICAGO, ILLINOIS, ASSIGNOR, BY MESNE ASSIGNMENTS, TO BASH OIL AND REFINING COMPANY, OF CHICAGO, ILLINOIS, A CORPORATION OF DELAWARE.

METHOD OF AND APPARATUS FOR TREATING PETROLEUM.

1,382,727.

Specification of Letters Patent. Patented June 28, 1921.

Application filed August 25, 1916. Serial No. 116,901.

To all whom it may concern:

Be it known that I, DANIEL W. HOGE, a citizen of the United States, residing at Chicago, in the county of Cook and State 5 of Illinois, have invented certain new and useful Improvements in Methods of and Apparatus for Treating Petroleum, of which the following is a specification.

This invention relates to a method of and 10 apparatus for treating petroleum and has for one of its objects the provision of a substantially continuous method of recovering gasoline present as such in petroleum and of converting the residuum or a large proportion 15 thereof into gasoline.

A further object of my invention is the provision of an apparatus for treating petroleum to recover therefrom the gasoline present as such therein and breaking down 20 the high boiling point compounds in the residuum into low boiling point compounds corresponding to gasoline.

A further object of my invention is the provision of a method of and apparatus for 25 conserving the heat necessarily used in converting the petroleum residuum into gasoline by utilizing a portion of the heat to release the gasoline present as such in the petroleum.

Other objects and advantages of my invention will be apparent as it is better understood by reference to the following specification when read in connection with the accompanying drawing, illustrating the preferred embodiment thereof, in which the figure is an end elevation partially in section 35 of an apparatus according to my invention and adapted to be employed in carrying out my method.

This method involves the use of a closed container adapted to hold a bath of petroleum which may be fed to the container from a source of supply, conducting cracked vapor from the cracking apparatus beneath the 45 surface of the bath of petroleum whereby the excess heat stored in the vapor is utilized to drive off the gasoline present as such in the petroleum and conveying the residuum from the container to a still where it is subjected to heat and vaporized, the vapor being then conducted to the cracking apparatus. The mixture of natural gasoline and cracked 50 vapor is conducted to a condenser where it is

liquefied, the liquid being subsequently refined in the usual manner. By the practice 55 of this method I am enabled not only to recover the natural gasoline present in the petroleum but to convert the major portion of the residuum into gasoline at a minimum expense. 60

Referring to the drawing, 1 indicates a still which may be of any usual or desirable form, the form illustrated being the cylindrical still commonly used in the art. The still 1 is heated by a furnace 2 in the usual manner. From a dome 3 of the still 1 a pipe 4 leads to a header 5 from which the vapor is distributed through pipes 6 to a plurality of units comprising the cracking apparatus.

The cracking apparatus includes one or 70 more units, each unit comprising a receptacle 7 adapted to receive a bath 8 of molten lead in which a plurality of pipes 9 are submerged, the pipes being connected at their ends to form a continuous conduit through 75 which the vapor from the pipe 6 is conducted. A cover 10 closes the receptacle 7. The receptacle 7 is supported on a suitable furnace 11 which may be heated by means of oil burners 12 or in any other suitable 80 manner.

A closed cylindrical container 13 of approximately half the diameter of the still 1 and substantially equal thereto in length is mounted adjacent the cracking apparatus 85 and is adapted to contain a bath of petroleum supplied from a source of supply through the pipe 15. A pipe 16 connects the end of the conduit formed by the pipes 9 to the interior of the container 13, the end 17 90 of the pipe 16 being submerged in the petroleum within the container 13. A steam coil 18 is disposed within the container 13 and may be supplied with steam from any suitable source through the pipe 19 when 95 conditions are such as to require additional heat to accomplish the desired result. From the dome 20 of the container 13 a pipe 21 leads to a condenser 22 wherein the mixture of natural gasoline and cracked vapor is 100 liquefied. A pipe 23 leads from the bottom of the container 13 to a pump 24 which is in turn connected by a pipe 25 to the interior of the still 1, the pipe 25 entering the still 1 above the liquid line therein. A trap 105 26 is provided in the pipe 6 to collect any

liquid which may enter the pipe and is connected by a pipe 27 to the interior of the container 13.

The mode of operation of my method and apparatus will be readily understood from the following brief description thereof. In starting a quantity of petroleum residuum, commonly known as fuel oil, is supplied to the still 1 wherein it is heated and vaporized, the vapor passing under a low pressure to the cracking apparatus where it is subjected under conditions which permit the major portion of the vapor to contact with the walls of the pipes 9 to a temperature 15 ranging from 75° to 1250° F. depending upon the character of the vapors being treated. Under these conditions the high boiling point compounds in the vapor are broken down or cracked into compounds 20 having relatively low boiling points analogous to those present in natural gasoline.

A supply of crude petroleum containing gasoline as such is supplied through pipe 15 to the container 13. The vapor from the 25 cracking apparatus is conducted beneath the surface of the bath of petroleum in the container 13 and the excess heat stored in the vapor is utilized to drive off the natural gasoline which mingles with the cracked 30 vapor and passes through the pipe 21 to the condenser 22. If additional heat is required it may be supplied through the steam coil 18. When the natural gasoline in the bath has been removed the pump 24 is started and 35 the residuum is thereby withdrawn from the container 13 and is sprayed into the still 1 above the level of the liquid contained therein. Any liquid which may enter the pipes 6 leading to the cracking apparatus is 40 trapped and conveyed by the device 27 to the container 13 so that only vapor is allowed to enter the cracking apparatus. Suitable valves are provided at all necessary points to regulate the operation of the 45 apparatus. When the apparatus has been in operation for a considerable period sufficient carbon may accumulate in the still 1 to prevent proper heating of the liquid therein whereupon it will be necessary to 50 shut down the apparatus and clean the still; otherwise the operation of my method and apparatus is substantially continuous. From the foregoing it will be apparent that I have perfected a method of and apparatus for 55 treating petroleum whereby it is possible to recover a much greater proportion of gasoline from petroleum than by methods now known and practised in the art. Furthermore, great economy in operation is effected 60 by reason of the utilization of the heat employed in cracking the vapor to drive off the natural gasoline from the crude petroleum and by the arrangement whereby the method becomes substantially continuous in opera- 65 tion.

Various changes may be made in the details of the method and apparatus as above described without departing from the spirit and scope of the invention or sacrificing any of its material advantages, the form 70 hereinbefore described being merely the preferred embodiment thereof.

I claim:

1. A method of treating petroleum which comprises, first, subjecting petroleum from 75 which free gasoline has been removed to heat in a still to vaporize the petroleum; second, conducting the vapor to a cracking apparatus and there subjecting the vapor to a temperature sufficient to break down the 80 high boiling point compounds into compounds having relatively low boiling points; third, conducting the highly heated cracked vapor from the cracking apparatus to a separate receptacle containing a bath of petroleum containing free gasoline and passing said vapor through said bath to heat the same and release the free gasoline therein; fourth, withdrawing the vapor and free gasoline from said receptacle and condensing the same; and fifth, conducting the 85 residuum of said bath to said still.

2. A method of treating petroleum which comprises, first, subjecting petroleum from 90 which free gasoline has been removed to 95 heat in a still to vaporize the petroleum; second, conducting the vapor to a cracking apparatus and there subjecting the vapor to a temperature sufficient to break down the high boiling point compounds into compounds having relatively low boiling points; third, conducting the highly heated cracked vapor from the cracking apparatus to a separate receptacle containing a bath of 100 petroleum containing free gasoline and 105 passing said vapor through said bath to heat the same and release the free gasoline therein; fourth, trapping any liquid which may collect in conducting the vapor to the cracking apparatus and conducting said 110 liquid to said receptacle; and fifth, withdrawing the vapor and free gasoline from said receptacle and condensing same.

3. An apparatus for treating petroleum which comprises a vaporizing still, a cracking apparatus, a pipe for conducting vapor from the still to said cracker, a receptacle separate from the cracker containing a bath of petroleum, a pipe for conducting the vapor from said cracker to said receptacle 115 and having its discharge end submerged in the bath in said receptacle, a condenser, a pipe leading from the top of the receptacle to the condenser, a pipe connecting the bottom of the receptacle to the still, and a 120 pump interposed in said last-mentioned pipe.

4. An apparatus for treating petroleum which comprises a vaporizing still, means for subjecting the vapor from said still to 130

temperatures sufficient to break down the high boiling point compounds of said vapor into compounds having relatively low boiling points, a pipe for conducting vapor from said still to said means, a closed container adapted to hold a bath of petroleum, means for conducting said vapor beneath the surface of said bath, an outlet from said container for conducting vapor therefrom,

a condenser connected to said outlet, means for trapping liquid in said pipe and conveying it to said container, and means for conveying petroleum residuum from said container to said still.
